PUMP

John H. Davis, Detroit, Mich., assignor to Jessie
 A. Davis Foundation, Inc., Detroit, Mich., a
 corporation of Delaware

Application June 30, 1947, Serial No. 758,172

14 Claims. (Cl. 103—88)

1

This invention is a novel improvement in pumps of the type shown in my co-pending application Serial No. 672,801, filed May 28, 1946, and the principal object thereof is to provide a pump radically differing in principle from the conventional type of pump, same having a conical shaped impeller carrying fins surrounded by a sleeve secured thereto and closely fitting the machined outer edges of the fins which are preferably spirally arranged so that the cone, fins, and sleeve rotate as a unit and impart to a liquid medium a velocity longitudinally of the impeller axis while building up a pressure radially from intake to discharge by centrifugal force, such pressure and velocity being governed by the rotational speed, diameter of the impeller and lead of the fins.

A further object of the invention is to provide a pump of the above type which will be simple, novel and efficient in operation, and will be capable of delivering a wide range of fluid capacity by merely regulating the speed of the propeller, or the area of the outlet.

Other minor objects of the invention will be hereinafter set forth.

I will explain the invention with reference to the accompanying drawings, which illustrate one practical embodiment thereof to enable others familiar with the art to adopt and use the same; and will summarize in the claims the novel features of construction, and novel combinations of parts, for which protection is desired.

In said drawings:

Figure 1 is a side elevation of my novel pump showing in dotted lines the arrangement of fins on the impeller.

Fig. 2 is a vertical section on the line 2—2, Figure 1.

Fig. 3 is a side elevation showing the impeller cone head with fins thereon, detached.

Fig. 4 is a vertical section through the impeller cone head and fins, taken on the line 4—4, Figure 3.

Fig. 5 is an end view of the cone head showing the shape and arrangement of the fins thereon.

Fig. 6 is an enlarged vertical section through the upper impeller shaft bearing showing the adjacent parts.

As shown in Figs. 1 and 2, my pump comprises a casing 1 having a conical impeller chamber 1a therein adapted to house the impeller hereinafter described, said casing 1 having an inlet 1b at the smaller end of the chamber 1a, preferably but not necessarily of substantially elliptical shape, said inlet 1b having a lateral flaring inlet 55

2

port 1c, as shown in Fig. 1, terminating in a bolting flange 1d whereby the pump may be secured to the side of the tank with the inlet port 1c registering with the outlet of the tank, said flange 1d being preferably provided with bolt-receiving holes arranged in any desired manner. By the above construction, the water from the tank entering inlet port 1c at the bottom of the casing 1 passes into the inlet 1b which registers with the smaller end of the impeller chamber 1a.

Alternatively, inlet port 1c may be closed by a plate (not shown) secured to the flange 1d, and an inlet pipe 1e (Fig. 1) may be tapped into a threaded bore 1f in the base of the inlet 1b, directly upon the impeller axis, said bore 1f being normally closed by plug 1g (Fig. 2) when the inlet port 1c is used. When the fluid is supplied by inlet pipe 1e, the water enters the inlet port 1b in alignment with the axis of the impeller, 20 hereinafter described.

The casing 1, at the larger end of the impeller chamber 1a, is thickened as at 1h and provided with a series of bolt holes 1j for the reception of bolts 2 which secure a cap casing 3 thereto, 25 the cap 3 closing the upper end of the impeller chamber 1a of casing 1. At the upper end of casing 1, the inner wall is arcuately recessed as at 1m, the same curving outwardly and upwardly with its inner end registering with the upper end 30 of the conical impeller chamber 1a, as shown in Fig. 2.

The cap 3 is rounded on its upper surface, as shown in Figs. 1 and 2, the same having an outlet 3a adapted to be connected with a discharge pipe 3b having a valve V therein (Fig. 2) so as to permit control of the volume of fluid passing therethrough. Cap 3 is provided with an upwardly extending lug 3c which is bored coaxially with the impeller chamber 1a, as at 3c, to receive the upper anti-friction bearing 4 (Fig. 6) of the impeller shaft 5 which passes downwardly through a cylindrical housing 3d formed on the under side of the top of cap 3. Lubricant may be introduced into the cylindrical housing 3d through a fitting 45 3e to lubricate the upper and lower anti-friction bearings 4 and 10 of shaft 5.

Above the lug 3c is a head 6, preferably secured thereto by cap screws 7 or the like, said head having a bore 1a through which the upper end of shaft 5 passes for connection with a prime mover (not shown), suitable sealing means 8 being provided within the head 6 to prevent passage of fluid upwardly through the cap 3 along the shaft 5. Within the enlargement of the head 6 is a lock nut 9 threaded upon a reduced portion of

shaft 5 and directly engaging the inner race of the anti-friction bearing 4 for preventing axial movement of said bearing 4 with respect to the shaft. Any other form of bearing 4 and packing 8 for the shaft 5 may be substituted for that shown in Fig. 6, the particular form of bearing and packing forming no part of my present invention.

The lower end of cylindrical housing 3d. of cap 3 has an enlarged bore 3e to house the lower anti-friction bearing 10 of shaft 5, below which is disposed a spacing washer or collar 11, below which is a packing 12a around the shaft 5. On shaft 5 below packing 12 is mounted the impeller cone head 13 hereinafter referred to, same having a bore 13a receiving the lower end of the shaft 5 and being secured thereon by means such as a pin 14. However, any other means of securing the impeller head 13 to shaft 5 might be utilized.

Preferably the impeller head 13 is substantially cone-shaped with its apex disposed downwardly, as shown in Fig. 4, the upper larger end portion of the head being hollowed or recessed as at 13b; and a spring 15 is disposed around the shaft 5 between the top of the impeller head 13 and the packing 12 to maintain the packing and spacing washer 11 in the operative position shown in Fig. 2; a washer 12a being preferably disposed below the packing 12 to be engaged by the spring 15.

As shown in Fig. 2, the upper end of the impeller cone head 13 is disposed flush with the lower end of the arcuate portion 1m of the impeller chamber 1a of casing 1; and on the outer surface of the impeller are a plurality of spiral ribs or fins 16 which are shaped as shown in Figs. 3, 4 and 5 but may be somewhat modified as desired, said fins being of less depth at their upper ends than at their lower, and the lower ends of the fins terminating at the lower end of the impeller chamber 1a, and being triangularly shaped as at 16a as shown more particularly in Fig. 3. Preferably one edge of each of the fins 16 has a lead of substantially 15", while the other edge has a lead of substantially 18", so as to prevent formation of a vacuum on the back surfaces of the fins.

The outer edges of the fins are spaced from but parallel with the wall of the impeller chamber 1a; and mounted upon the outer edges of the fins extending the full length thereof is a conical sleeve 17 spaced from but parallel with the wall of impeller chamber 1a, said sleeve 17 being welded, brazed, or otherwise rigidly secured to the impeller fins so as to rotate with the head 13 as a unit. Preferably the ends of the impeller chamber 1a are formed as at 1n and 1p to make a close running fit with the ends of the sleeve 17 to prevent sediment from readily becoming lodged between the sleeve 17 and the wall of impeller chamber 1a, the clearance at the outlet 1n being substantially three times the clearance at the inlet 1p so that the passage of fluid through the impeller 13, 16, 17 will create a vacuum tending to suck any sediment, grit, sand or the like from between the cylinder 17 and the wall of the impeller chamber, thus maintaining said space clear of extraneous foreign matter. Preferably, the clearance between the lower end of the sleeve 17 and the lower end of the ribs 16 is approximately .005", more or less, the purpose of the clearance being to avoid friction between the parts.

As shown, the distance between the cone head 13 and the sleeve 17 lessens towards the upper end of the impeller, and in alignment with the cone head 13 at the upper end of the impeller chamber 1a is a ring 18, the outer surface of which forms a continuation of the outer ends of the fins 16 of

the impeller at the upper end of the chamber 1a, said ring 18 terminating at the top of the casing 1. Ring 18 is provided with a hub 18b which has a pressed fit around the enlarged lower end of the cylindrical housing of the cap 3. The clearance between the lower end of the ring 18 and the top of the cone head 13 is approximately .015".

Ring 18 carries on its exterior a series of short fins 18a (Fig. 2) disposed at approximately 30 degrees to the axis of the shaft 5, said fins having their outer ends conforming with the arcuate wall 1m in the top of the casing 1 so as to make a close fit therewith. The object of the fins 18 is to convert the rotary motion of the fluid when leaving the impeller chamber into rectilinear motion, i. e., movement substantially axially of the shaft 5 before the water passes into the cap 3. While I have indicated three fins 18a may be utilized on the ring 18, obviously a greater or lesser number may be used, and the fins may be arranged at various angularities to convert the rotary motion of the fluid leaving the impeller into a substantially rectilinear motion when entering the outlet ports 3h in cap 3 which lead to the outlet 3a.

Cap 3 contains a core 3g extending from the upper end of the ring 18 and being substantially parallel with the upper wall of the cap 3, although the distance may be slightly increased towards the outlet 3a, said space being denoted by the reference numeral 3h.

In operation:

By the above construction, water entering the inlet 1b of the casing 1 through the pipe 1e (or the inlet 1c) is raised by atmospheric pressure into the lower end of the impeller 13, 16, 17 where the water is caught by the ribs or fins 16 of the impeller and passed upwardly between the cone head 13 and the sleeve 17 between the fins or ribs 16, the weight of the water acting as a flywheel so that as the shaft 5 is rotated a tremendous centrifugal force is built up within the impeller, causing the water to pass upwardly into the cap 3. As the shaft 5 is rotated, the impeller 13, 16, 17 rotates therewith and the rapid increase in diameter of the impeller cone 13, combined with the high pitch of the spiral fins 16, and the angularity of the sleeve 17 around the fins 16 will cause the liquid pressure within the impeller to gradually build up parallel with the impeller axis, forcing the liquid upwardly through the impeller 13, 16, 17 between the fins 16 while building up a high pressure radially, due to the centrifugal force, which pressure reacts upon the conical sleeve 17 to exert an axial component, whereby, as the liquid emerges from the upper tips of the ribs 16, the liquid in sleeve 17 is given a strong swirling motion and a rapid movement towards outlet 3a, which swirling motion, however, is counteracted before reaching the cap 3 by the ribs or fins 18a of ring 18, as a result of which the flow of liquid is caused to proceed in a substantially rectilinear direction with respect to shaft 5 when passing towards the outlet 3a.

The quantity of liquid delivered through the outlet 3a may be varied by varying the speed of rotation of the impeller, or by adjusting valve V in the outlet pipe P.

My pump will have a wide range of capacity depending upon the adjustment of the valve V, whereby the pump may be continued to be run at full speed while delivering only a small capacity without injury thereto, as no back pressure is built up therein to injure the pump. This feature is an important improvement over con-

ventional pumps designed for only one capacity and which must be driven at the designed speed to deliver such capacity, for in my pump, as the valve V is closed, the power to rotate the impeller at the same speed becomes less rather than greater.

In actual practice my pump, while pumping 6000 gallons per minute, has had its capacity reduced to only five gallons per minute by regulating the valve V beyond the outlet 3a, with a corresponding decrease in power necessary to rotate the impeller.

My pump operates somewhat similar to that disclosed in my companion application Serial No. 672,801 aforementioned, but in the present invention the shaft enters the pump casing adjacent the outlet end rather than the inlet end.

In my pump it will be noted that there is no friction between the water in its passage through the impeller and any stationary parts of the casing, the water being engaged only by rapidly rotating surfaces, thereby cutting down or reducing liquid friction to a minimum.

I do not limit my invention to the exact form shown in the drawings, for obviously changes may be made therein within the scope of the claims.

I claim:

1. A liquid pump, comprising a casing having a substantially conical impeller chamber progressively contracting towards one end into an inlet, said casing being open at the larger end of the chamber; a cap closing the open end of the casing and having an outlet; a driven shaft journaled in the cap coaxially of the chamber; an impeller on said shaft within the chamber and comprising a substantially cone-shaped head progressively enlarging towards said cap, a series of spirally arranged ribs on said head spaced from the wall of the chamber, and a sleeve surmounting the ribs and rotatable with the head and embracing the length of the ribs and having a slight clearance from the wall of the chamber; the spacing between the head and sleeve progressively decreasing towards the larger end of the impeller; and a fixed ring within the casing adjacent the cap and having fins therein adapted to convert the rotary motion of the liquid emerging from the impeller into rectilinear motion within the ring before passing into the cap.

2. In a pump as set forth in claim 1, said ring forming a continuation of the larger end of the head and terminating flush with the larger end of the casing, and said fins being disposed between the ring and casing.

3. In a pump as set forth in claim 1, said ring forming a continuation of the larger end of the head and terminating flush with the larger end of the casing; said fins being disposed between the ring and casing; and a core in said cap forming a continuation of the ring, said core being spaced from the inner wall of the cap and providing a channel therein leading to the outlet.

4. In a pump as set forth in claim 1, said cap having a cylindrical housing therein coaxial with said impeller in which said driven shaft is journaled; and said ring being mounted on said cylindrical housing.

5. In a pump as set forth in claim 1, said cap having a cylindrical housing therein coaxial with said impeller in which said driven shaft is journaled; said head being recessed at its larger end; and a packing on said shaft adjacent the lower end of the housing; and a coiled spring

around the shaft interposed between the head and packing.

6. In a pump as set forth in claim 1, said ribs extending below the smaller end of the head and being triangularly shaped adjacent the inlet; the opposite side walls of the ribs having different pitches to prevent formation of vacuum by passage of fluid along the ribs.

7. In a pump as set forth in claim 1, the clearance between the sleeve and wall of the chamber at the larger end of the sleeve being substantially three times that at the smaller end of the sleeve, whereby the space between the sleeve and wall of the chamber will be maintained substantially free from sediment during operation.

8. A liquid pump, comprising a casing having a substantially conical impeller chamber progressively contracting towards one end into an inlet, said casing being open at the larger end of the chamber; a cap closing the open end of the casing and having an outlet; a driven shaft journaled in the cap and entering the larger end of the chamber coaxially thereof; an impeller on said shaft within the chamber and comprising a substantially cone-shaped head progressively enlarging towards said cap and terminating adjacent the larger end of said chamber, a series of spirally arranged ribs on said head having a steep pitch, said ribs being spaced from the wall of the chamber, and a sleeve surmounting the ribs and rotatable with the head and embracing the length of the ribs and having a slight clearance from the wall of the chamber; the spacing between the head and sleeve progressively decreasing towards the larger end of the impeller; and a fixed ring within the casing adjacent the cap and having fins therein adapted to convert the rotary motion of the liquid emerging from the impeller into rectilinear motion within the ring before passing into the cap.

9. In a pump as set forth in claim 8, said ring forming a continuation of the larger end of the head and terminating flush with the larger end of the casing; said fins being disposed between the ring and the casing; and said ring being non-rotatably mounted on said cap.

10. In a pump as set forth in claim 8, said ring forming a continuation of the larger end of the head and terminating flush with the larger end of the casing; said fins being disposed between the ring and the casing; and a core in said cap forming a continuation of the ring and being spaced from the inner wall of the cap and providing a channel therein leading to the outlet.

11. In a pump as set forth in claim 8, said cap having a cylindrical housing therein coaxial with said impeller in which said driven shaft is journaled; said ring being fixedly mounted on said cylindrical housing; and means for preventing passage of liquid from said chamber along the said shaft.

12. In a pump as set forth in claim 8, said cap having a cylindrical housing therein coaxial with said impeller in which said driven shaft is journaled; and means for preventing passage of liquid from said chamber along the said shaft comprising a packing on said shaft adjacent the lower end of the housing; and a coiled spring around the shaft interposed between the head and packing.

13. In a pump as set forth in claim 8, said ribs extending below the smaller end of the head and being triangularly shaped adjacent the inlet; the opposite side walls of the ribs having different

pitches to prevent formation of vacuum by passage of fluid along the ribs.

14. In a pump as set forth in claim 8, the clearance between the sleeve and wall of the chamber at the larger end of the sleeve being substantially three times that at the smaller end of the sleeve, whereby the space between the sleeve and wall of the chamber will be maintained substantially free from sediment during operation.
